(57) **CLAIM**

The ornamental design for a shuttle car as shown and described.

DESCRIPTION

FIG. 1 is a perspective view of a fifth embodiment of a shuttle car showing our new design from the top, front, and left side;

FIG. 2 is a perspective view thereof shown from the top, rear, and right side;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is a rear elevation view thereof.

The broken lines illustrate portions of the shuttle car that form no part of the claimed design.

1 Claim, 6 Drawing Sheets
